US00D550733S

(12) **United States Design Patent** (10) **Patent No.:** **US D550,733 S**
Wright (45) **Date of Patent:** **** Sep. 11, 2007**

(54) **CURVED SLOTTED GROUNDED JAW**

(75) Inventor: **Douglas F. Wright**, Tucson, AZ (US)

(73) Assignee: **Engineering & Research Associates, Inc.**, Tucson, AZ (US)

(**) Term: **14 Years**

(21) Appl. No.: **29/275,748**

(22) Filed: **Jan. 5, 2007**

(51) **LOC (8) Cl.** **15-99**

(52) **U.S. Cl.** **D15/146**

(58) **Field of Classification Search** **D15/21, D15/28, 138, 139, 145, 146; 156/273.7, 156/274.4, 274.6, 358, 380.1, 380.3, 380.6, 156/380.7, 477.1-489, 583.9; 219/632, 736, 219/757, 765, 769, 770, 774, 777, 778**

See application file for complete search history.

(57) **CLAIM**

The ornamental design for a curved slotted ground jaw, as shown and described.

DESCRIPTION

FIG. 1 is a top right isometric view showing my design, the tubing sealer shown in dashed lines illustrates the environment of my invention and forms no part of the claimed design;

FIG. 2 is a right top rear isometric view thereof;

FIG. 3 is a right top front isometric view thereof;

FIG. 4 is a top plan view thereof;

FIG. 5 is a front elevational view thereof;

FIG. 6 is a rear elevational view thereof;

FIG. 7 is a bottom plan view thereof;

FIG. 8 is a left side elevational view thereof; and,

FIG. 9 is a right side elevational view thereof.
